UNITED STATES PATENT OFFICE.

WILLIAM F. CREMEAN, OF WILKES-BARRE, PENNSYLVANIA.

RAILWAY-CAR.

1,336,134.

Specification of Letters Patent.

Patented Apr. 6, 1920.

Application filed May 3, 1919. Serial No. 294,369.

To all whom it may concern:

Be it known that I, WILLIAM F. CREMEAN, a citizen of the United States, residing at Wilkes-Barre, in the county of Luzerne and State of Pennsylvania, have invented new and useful Improvements in Railway-Cars, of which the following is a specification.

This invention relates to railway cars of the drop bottom or hopper bottom type, and in particular to an improved arrangement of door securing parts and lifting and locking mechanism.

Heretofore difficulties have been experienced in the complete closing of the doors of hopper bottom cars, due to the warping or springing of the doors and to other causes, so that considerable loss of ore, coal or other material loaded on the car occurred, due to spillage through the unclosed spaces between the partly closed doors and the car bottom. For example, in the hopper door appliances now generally in use, it is often found impossible to properly close the doors, when these are warped or sprung, as the door securing latch or hook, as at present shaped, often either cannot be brought to engage the door at all, or hold it snug against the hopper bottom.

The object of my invention is to avoid these and other difficulties by providing mechanism by which a door that does not close properly may be conveniently and quickly lifted into place and securely locked.

Other objects of the invention will manifest themselves from the detailed description thereof and manner of applying and using the same to be presently disclosed.

The invention consists of structural characteristics and relative arrangements of elements which will be hereinafter more fully described and particularly pointed out in appended claims.

In the drawings, in which similar reference characters indicate the same parts in the several figures,

Figure 1 is a side elevational view of one form of the hopper door securing device and portion of a car to which it is attached;

Fig. 2 is a sectional view taken on line II-II of Fig. 1;

Fig. 3 is a vertical sectional view taken on line III-III of Fig. 1;

Fig. 4 is a side elevational view of a modified form of my device, and

Fig. 5 is a sectional view taken on line V-V of Fig. 4;

In the drawings, the car body is represented as having sides 10 and a hopper bottom provided with the usual discharge opening not shown. Adapted to close the latter and fastened to the hopper bottom a pair of transversely disposed, hinged doors 11 are provided. These doors are located with their free edges adjacent each other and are supported on long hinge bars 12, movable on pintles 13 disposed transversely of the car and so that the doors are adapted to swing toward each other into closed position.

Fastened to the lower sides near the inner edges of each of the doors are angle-irons 14 serving to stiffen the doors and extended outwardly a short distance beyond the latter, on each side, so as to provide convenient ledges to be engaged by the door hooks 15. These hooks are provided with integral pivot lugs 16 journaled in outer and inner brackets 17 and 18, respectively, which are riveted to the car sides 10. The hooks for each pair of doors are turned to swing parallel with the side of the car toward the free edges of the doors, in opposite directions, and are adapted to engage the angle irons 14 of the doors, being pivoted with respect to their centers of gravity so that they will fall by gravity into engaging positions.

The locking face or supporting ledge 19 and the auxiliary supporting face or ledge 20 of each hook are shaped to conform to the flat leg or locking face of the projecting angle iron 14, and are so disposed that a vertical plane drawn through the axis of the pivots will be normal to the locking faces when the doors are closed. The hooks therefore tend to hold the doors closed.

Each hook 15 is provided on its lower rear edge with a lug or projecting portion 21 adapted to serve as a bearing or fulcrum for lifting the door into a closed position. In the modification shown in Fig. 4, this lug or projection is provided on the outer lower side of the hook and is indicated by the numeral 22. In this modification also the auxiliary supporting face 20 of Fig. 1 is not incorporated.

A gravity eccentric cam 23, pivoted to the car side on the bolt 24, is supplied for each

hook for the purpose of firmly and securely locking the hooks and therefore the doors in their closed position in every position of the car and while it is being transported from mine to destination.

The operation of my lifting and locking mechanism is as follows: When, as often happens, the hopper bottom door will not close completely, as shown on the left side 10 of Fig. 1, it may be held on the auxiliary supporting face or ledge 20 of the hook, while being lifted by hand to its normal closed position by means of a bar B, fulcrumed on the lug 21, the door being raised 15 from the supporting face 20 until it rests on the locking face 19, and finally pushed home, as shown on the right side of Fig. 1. The bar B in Fig. 1 is of course held approximately normal to the plane of the car 20 side.

In the modification of my device, shown 25 in Fig. 4, when the unclosed door is in the position shown on the right side of Fig. 4, the bar B is held approximately parallel to the side of the car, fulcrumed on the lug 22 and engaged with the flat leg of the angle-iron 14. By lowering the outer end of the 30 bar B the door may readily be lifted to the position shown on the left side of Fig. 4 and securely locked in position.

It is obvious that various other forms and modifications may be made without departing from the essential features and principle of my invention and I do not wish to be 35 understood as limiting myself to the specific and preferred construction herein shown and described.

What I claim is:—

1. As a new article of manufacture in 40 hopper bottom door securing devices, a pivoted hopper bottom door engaging hook provided with a door engaging ledge, an auxiliary supporting ledge located below the former and a lug or projecting portion 45 adapted to serve as a support for means for

raising the door from support on the latter ledge to the former.

2. The combination of hopper bottom car doors and securing devices comprising door engaging hooks, each provided with a door 50 engaging ledge and a lug or projecting portion adapted to serve as a support for movable door raising means and coacting with said ledge.

3. In hopper bottom car door securing devices, a hook having door engaging means and provided with a projecting portion so constructed and arranged as to be adapted to receive movable door raising means and serve as a fulcrum therefor. 55

4. A railway car having a movable door, a hook pivoted to the car and adapted to engage said door and to hold the same in closed position, a cam also pivoted to the car and adapted to hold the said hook in engaged relationship with the door, the said hook being provided with an auxiliary ledge and a projecting portion by means of which the door may be raised from a partly closed 60 to a fully closed position. 65

5. A railway car having a body and movable door, an outer bracket attached to and spaced from the outer side of the body, a hook having integral and oppositely disposed pivot lugs journaled in said outer 70 bracket and car body and adapted to engage said door and hold the same in closed position.

6. A railway car having a body and movable door, an outer bracket attached to and 75 spaced from the outer side of the body, an inner bracket attached to the inner side of the body, a hook having integral and oppositely disposed pivot lugs journaled in said outer and inner brackets and adapted to engage 80 said door and hold the same in closed position.

In testimony whereof I affix my signature.

WILLIAM F. CREMEAN.
